corporation of New York

Application December 27, 1941, Serial No. 424,582

22 Claims. (Cl. 101—401.2)

This invention relates to indirect photomechanical reproduction and includes printing surfaces that can be utilized in typography. The system is indirect because the printable values are firstly obtained in reversed relief by developing a special element into a mould from which a final printing surface may be cast. The invention comprises means, ways and products.

In most photorelief processes it is sufficient to reverse the steps to produce a mould instead of a printing surface; this is done by using a positive instead of a negative as a master record, or by etching away values that are usually hardened and preserved, with the occasional variation of reversing also the direction of the exposure in order to utilize as bottom in the mould the even surface of the support carrying the sensitive coating. Examples of such indirect way of producing printing surfaces may be found in the literature of the early art; among other suggestions Namias proposed to expose the plate through a transparent support, and Waterhouse to produce an image on a carbon tissue and transfer and develop it on a metallic plate; in those and similar processes, however, the production of half-tone plates makes necessary to firstly transform the photographic values into photomechanical ones in the known process-record, where the tones appear divided in sections of different areas; and further, when the steps are reversed, and instead of a printing surface a mould is obtained, the casting of the final plate constitutes an additional step, for such methods, rather than indirect are reversedly practiced direct ones.

The production of half-tone printing blocks without a process record, by exposing under an ordinary negative a sensitive coating having depressions or recesses decreasing in cross-sectional area, was suggested in a method of direct photomechanical reproduction described in Patent No. 2,234,997, issued March 18, 1941. The sensitive element utilized in that direct method includes two forms; in one of them the depressions are filled with a transparent support through which the element is exposed, and in the other form the depressions are not filled, for the final support is provided after the exposure, the sensitive coating being provisionally carried by a porous temporary support. Of these forms the first cannot be reversedly processed to produce a mould, for neither the use of a positive instead of a negative, nor the etching of the values that are usually preserved, would render such result due to the already existing high-light projections. In the second form, however, the order in which the steps of the processing are performed offers at least an opportunity for the indirect production of a printing surface, provided some previous modifications are made in both the support and the sensitive coating of the element. For this

I may use, instead of a porous an impermeable rigid support and, instead of a soluble coating, a thickness of hardened silver emulsion. When in such modified element, on the side having the depressions, a photographic image is produced, developed, and etched in known manner, a mould is obtained; and when a cast is taken therefrom no additional step is performed; for what would have been a support for the exposed depressions in the direct system, now fills the etched cavities and becomes shaped, instead of furnishing as before a high-light foundation with additional values of hardened gelatine. The new product is better and preferable, for the final block, as made of a single substance, is more resistant. Such indirect method of reproduction is not a reversedly practiced form of my direct system, for the means utilized are different; after the modifications introduced in the support and coating of the element it is not possible anymore to directly produce with it a printing surface but a mould. It is, however, a variation of my formerly patented direct method, for it utilizes the same basic and claimed step of transforming the photographic values into photomechanical ones by "photographically recording light values on a light sensitive body provided on the exposure side with minute depressions decreasing in cross-sectional area and sharply ending on the other side."

The described variation was yet the point of departure in the development of the present invention. Photoreliefs of gelatine and other equivalent substances are the subject of certain precautions in typographic printing, for although most objections formerly made to such type of elements are today overcome by suitable treatments, there is always the possibility of careless handling for materials extremely sensitive to dampness and which may have to undergo the test of steam and pressure, as when mats are dried on the form in the stereotyping process. When such totally or partially colloidal plates are used as moulds, there are also limitations in regard to the possible system of casting, especially in electrolytic solutions. For these reasons, after having eliminated the colloidal matter from the final plate, I endeavored to also produce an all purpose mould, susceptible of serving in any system of casting and for any kind and number of duplicates.

I have found that the demarcation of the etchable zones by the effect of light, was not necessarily indispensable in producing photomechanical values in a soluble element shaped as the one utilized in the invention. The practical realization of that achievement may be understood by producing in a plate of a soluble substance several small depressions or recesses decreasing in cross-sectional area, having the same shape, and sharply ending at the same plane; if that plate

is treated by a solvent, so that some of the cavities be preserved, some others dissolved for a given time, and the remainder for a longer time, it will be seen that the dissolved cavities are enlarged figures geometrically similar to the undissolved ones, and that the respective sections at the original ending plane substantially correspond to the printing area of high-light, half-tone and shadow dots. Now, if those small depressions or cavities are suitably disposed in a copper plate as to provide a high-light casting pattern, and the plate is etched, with a solution of ferric chloride, proportionally to the values of a photographic image, it also will be seen that the copper foundation or ground has been developed into an excellent mould for a half-tone block reproducing all the tones of the image, and showing values in surface formed by small areas or dots of different sizes similar to those produced in the photoengraving process.

As to the manner of proportioning the etching to the values of an ordinary photographic record, there are several known reactions which may be utilized, including both the direct and catalytic action of a photographic image, to make active or to free certain reagents, and even to determine the electrical discharge of matter. I prefer, however, to use a gelatine resist in which the permeability is proportional to the values in depth and fully controllable, for among the varied resources of the art it is one of the practical ways of performing the selective etching of the high-light casting ground utilized in the invention. I found that a gelatine layer carrying an image, as a carbon tissue print, for instance, adhered under water to such uneven surface as that of a plate having depressions or recesses forming a high-light casting ground, will, during the process of drying, absorb the water retained by the small cavities and become substantially attached by suction to said cavities, just as if the surface were as smooth and even as an unetched plate or cylinder. And I also found that it further behaved through the developing and etching operations as an ordinary resist in intaglio processes.

The development of photographic values into photomechanical ones by the effect of etching is not new in general, for such technique is utilized in photogravure. However, in the known process the etching proceeds downwards from an even surface, and whatever be the area initially dissolved, it remains nearly the same for a given cavity at different depths, and also for other cavities initially having the same area; because in photogravure the photographic values in depth are transformed into photomechanical values also in depth, these values consisting in cavities or pockets more or less profound in which different thicknesses of fluid ink are deposited for the printing. In the present invention the etching does not proceed from an even surface but from within depressions or recesses sharply ending at the same plane; as a result of the etching operation those depressions are widened and, when the time of etching is not the same for all the cavities, a sectional plane at or near the original depth of the recesses will show sections of different areas corresponding to the extent in which the widening had been developed in each cavity. The photographic values in depth are thus automatically transformed while the etching goes on into photomechanical values in surface, as those produced by the photoengraving process.

The indirect system thus permits producing a

printing surface by selectively discharging matter from an element of special structure, which can be either sensitive to light or totally insensitive, a photographic image in the first case being produced in the element for the demarcation of the etchable zones, while in the second case the image is obtained elsewhere and according to the described example, transferred on the element to control the etching time. In this second, preferred form, a printing surface can be produced not only without a process or screened master record, but even without the previous optical transformation of the photographic values into photoengraving ones that takes place when utilizing a sensitive form of the element. The etching of the totally insensitive to light casting ground automatically develops those printing values, while the casting relief is made, as being in potential state in the combination of means and ways of the invention. Besides etching, the discharge of matter may also be produced in other equivalent ways, and as such discharge is essential in most relief processes for typographic purposes, the fact that it performs two functions represents a great simplification.

When comparing the two forms of the indirect system, one based on a sensitive, and the other on a non-sensitive structure, it may be observed that the effect of light in the first, and that of the etching in the second, are so similar within a moulding cavity decreasing in cross-sectional area, that the two phenomena seem to develop the same results. There are, however, certain advantages in favor of the etching step. Disregarding a slight irradiation within a sensitive coating, light only proceeds in a straight way, thus acting in depth; while etching acts both in depth and side-ways; and for that reason the sort of lateral effect of light in the sensitive element has to be created by prolonged exposure of a special structure presenting different decreasing resistances at different depths. In the case of etching the lateral action already exists and it seems rather augmented within the same structure. This explains why when light-values representing a photographic image fall within the cavities of my sensitive structure it is indispensable that an insensitive support should stop the light effect and develop the values in surface, for both the structure and the sectional plane at the bottom of the cavities are necessary for the optical transformation of the photographic values. While in the etching proper, of an insensitive structure, only one or the other of the two features is essential; for if the cavities do not decrease in cross-sectional area but just have a sharp end, it would be sufficient that the etching be limited by an unetchable substance at the bottom of the ground for selectively enlarging some of those cavities by a prolonged treatment, and this on account of the existing lateral effect of etching; on the other hand, if the cavities are shaped as to decrease in cross-sectional area without any arrangement to stop the etching, the already existing lateral effect of etching is so increased by the structure and becomes so predominant that the values at the bottom of the mould are developed before any objectionable difference in depth is produced. The ending planes, of such differently etched values, are so near in that case that plates cast therefrom are perfectly print-able.

When utilizing the etching step, it is, of course, desirable for a neat dot, that all the values be on the same printing plane; and, to save etching

time, that the cavities should also decrease in cross-sectional area. The printing values may be obtained on the same plane by mechanically eliminating in the cast the excess of height of half-tone and shadows, but it is preferable to do so in the mould, by forming the element of two substances, a soluble thickness carrying the depressions or recesses, and an insoluble second thickness supporting it at the ending plane of the cavities. In this manner the etching in depth is limited and the values are developed on the same printing plane.

By utilizing the etching step instead of the exposure step, as the element does not require to be sensitive to light, this widens the choice of suitable matter for the developable moulding element; substances can be chosen which are not permeable and will dissolve without swelling, as metals, for instance. In so doing, time is saved in the drying, for there is not any water absorbed by the element to dispose of, and the fact that the ground is not penetrated by photographic solutions prevents even the slightest distortion, a circumstance most desirable in making part plates. As to the resulting mould, it will be suitable for wet, dry, cold, hot casting, including embossing, stamping, vulcanizing, moulding of alloys, and electro-deposition, all without any special precautions.

The means and ways of the present invention lend themselves to many industrial applications, and in the art of printing to several kinds of work, but for the purpose of demonstration it will be sufficient to describe, in the following disclosure, the production of half-tone printing surfaces for which it is advantageously adaptable. Examples will also be found showing the possible varied and equivalent forms that such means and ways may present for different graphic purposes.

The invention is graphically described in the following drawing which illustrates sectional views, the ones showing the heavier shading corresponding to planes passing by the bottom of the small cavities present in the grounds where the moulds are developed. These views have been chosen as the best to demonstrate the invention and represent depressions in which the different reliefs are under the surface, while the views showing a lighter shading represent the casts or final plates which are reversed structures formed by projections:

Fig. 1 diagrammatically shows, in four stages, and for comparison, examples of means, ways, and products, in the indirect production of a printing surface by utilizing a light sensitive element.

Fig. 2 illustrates in four stages examples of means, ways, and products of the present invention in the indirect production of a printing surface from an element insensitive to light.

Fig. 3 presents a variation in the means shown in Fig. 2, for producing all the values on the same printing plane.

Fig. 4 is another variation of Fig. 2, both in means and ways, to produce tone and shadow values on the same raised plane, and lowered high-lights for pure white effect.

Fig. 5 is an example showing possible variations of ways in the practice of the invention.

Before entering into a detailed disclosure of the means, ways, and products of the invention it seems convenient to explain that both in their description and defining claims a geometrical language has been adopted to facilitate the understanding of structural requirements. Terms

are used such as cones, pyramids, bases, vertices, tangent or ending planes, similar figures, and the like. As such words usually convey an exact and mathematical meaning, it must be understood that, within the limits of operativeness, they are not purposed to so confine and restrict the invention in practical manufacture. The same remark must be made in regard to expressions describing requirements of matter, only purposed to materialize functions, or rather means to perform certain results, and which must not be construed as absolute but only as sufficient and operative for the purposes of the invention. Substances qualified as soluble or insoluble are only thus considered in regard to a given solvent, and even so in the extent necessary for the intended result, the insolubility being possibly partial, superficial, or artificially completed by an added protection, as long as such property is only utilized to stop the progress of the etching or discharge of matter from the body of the element utilized in the process.

For the purpose of comparison with the present invention I shall firstly describe how I may indirectly produce a printing surface by utilizing the element diagrammatically shown in the first stage of Fig. 1. This element is sensitive to light and, with some variations, has the same structure and sensitivity of one of the photographic materials described and claimed in Patent No. 2,234,997. As presented in Fig. 1, the element is formed by a waterproof, rigid support 2, carrying a coating of hardened silver emulsion 1, which has a number of small depressions or recesses 7, decreasing in cross-sectional area and sharply ending at the plane of contact between emulsion and support. The variations introduced in the new element consist in that the support is not porous and the emulsion is not soluble as in the element purposed for direct reproduction, for neither one are intended to be eliminated by washout, but the first to furnish the bottom of a mould and the second to maintain the shape of the depressions 7, through the photographic operations. The second stage in Fig. 1, shows the sensitive element after an image 3, has been produced and developed in it. The optical transformation of the values is there performed on the shaped emulsion in the same way as in my formerly patented direct method. The third stage in the same figure shows the casting values 4, after the image and surrounding gelatine have been etched away in known manner. In the fourth stage of Fig. 1, the final cast 11, of the indirectly produced casting surface is illustrated, the product being substantially identical in outline to the final plate described and claimed in the patent above referred to, except that the printing block is now formed by a continuous body in which not only the high-light dot 6, but all the printing values together with the supporting thickness are made of a single substance. Such new product is an improved printing surface which may be cast in varied substances and by different moulding systems consistent with the colloidal nature of the casting values 4, suitably hardened and protected. I prefer, however, to produce the same article by the indirect method of the present invention for it offers a wider choice both of substances and casting technique as I shall now demonstrate.

Fig. 2, shows, in four stages, means, ways and products of the present invention, which is not a variation of any direct system, but a genuinely indirect method purposed to produce, and which

can only produce, a moulding device from which the printing surface may be cast. The element illustrated in the first stage of the figure consists of a thickness of copper 6, having on the surface depressions or recesses 7a, decreasing in cross-sectional area and sharply ending substantially at the same plane. If a cast is taken from this shaped surface a block will be obtained which, after inked and printed, will furnish a high-light "tint," formed by small dots as those that represent the conventional "whites" in half-tone plates. Such element 6, is purported to be selectively etched in order to develop some of the high-light casting cavities into larger cavities for moulding half-tone and shadow printing dots. In regard to structure it is desirable that the angle of the cavities be as wide as possible, consistent with the known average printing depth of printable half-tone plates, a question fully discussed in Patent No. 2,234,997, issued March 18, 1941. It seems obvious that as the purpose of that requirement of width is to save etching time and to sufficiently develop the side etching of the cavities before they should attain any objectional depth, it is not indispensable that all the extent of the cavity should have a decreasing cross-sectional area provided the requirement is present near the bottom where they sharply end. The essential question in the structure of the cavities is that they constitute a moulding device for very light printing values which can be developed into darker values by etching or dissolving away matter from the inner walls of said cavities, and thus the developable ground of the rather unfinished moulding device must be so shaped or modified as to speed up the side etching in preference to the etching in depth. The form of cavity illustrated in the first stage of Fig. 2, has been adopted as most suitable for the purpose. As to matter, copper has been preferred for the example, to form the soluble thickness 6, because not only it is easily dissolved by ferric chloride, but will stand casting in any kind of moulding of known printing surfaces, at temperatures which never reach or approach the melting point of the metal. For casting type-alloy, brass would also do, as it is etchable in the same way; and so would aluminum, which can be dissolved in acidified solutions of the chloride, for castings conveniently under a terperature of 660° F. Zinc is another metal that could be utilized, for it is equally etchable, at least for the stamping of plastics which usually can be formed at temperatures under 300° F., thus giving a margin of more than 100 degrees before the melting of the metal. In addition to this, the choice is wide among natural and synthetic, organic and inorganic, simple or compound matter which can be suitably dissolved and if necessary cured or hardened by after-treatments. Obviously, substances that would do for cold moulding may not be satisfactory for stamping or embossing under heavy pressure, or would not stand certain temperatures or the immersion in solutions for electrolytic deposition; but while the system of casting in view will direct a convenient choice, copper seems the best for an all purpose developable moulding ground. The selection of a suitable substance for the etchable ground is not limited to compact and continuous thicknesses, for even the metals can be laminated and formed from powder and a suitable binder, all depending on the moulding to be performed. The selection of matter will also affect the production of the ground. When using copper, a master forming

plate may be produced by engraving crossed grooves on a thickness of brass, as the shaping plate described and claimed in the above cited patent, taking an impression of this in phenolic cured resin, and then duplicating the last. Or the master plate may be directly cut in steel to furnish a tempered die with which copper may be embossed or stamped. Instead of the pyramidal shape of the cavities, a conical form may also be secured by drilling the minute cavities in a small area of brass, and then multiplying the elements by casting, as type is made. The developable ground can also be produced by etching, especially for fine patterns, in well known manner. I prefer the crossed groove type of ground for it has less matter to be etched and besides shortening the processing time it furnishes very satisfactory values. For other substances a similar or other suitable way may be utilized which seems prolix to discuss. The general outline of the ground may also affect the manner of producing, it, as when a convex or concave cylindrical ground be desired, for which suggestions exist in the art that can be freely adapted to the purpose. Regarding the form of the dots, there is not a special limitation, for many graphic elements such as small squares, commas, straight or undulated lines, both regularly or irregularly distributed, would be satisfactory provided they furnish in their original shape a high-light pattern susceptible of being developed into similar larger values as those presented in the example. A suitable irregular ground may also be formed by dusting and etching; or from a swollen photorelief; or by evenly distributing cracked particles on a sticky coating in the manner of sand-paper or emery-cloth, until the repeated test furnishes a neat print of a high-light "tint" which is then duplicated and used as a shaping element. The number of cavities for a given area is only restricted in the example by the possibilities of the printing system adopted, and for the case of typography it may be practically fixed between a minimum of thirty and a maximum of two hundred and fifty depressions per lineal inch, other graphic purposes permitting to use coarser or finer patterns. In the second stage of Fig. 2, the insensitive element appears protected by a negative resist of gelatine 8, which may be separately printed from a photographic positive transparency and transferred and developed on the ground. After the resist is conveniently dry, the etching of the copper ground is made with ferric chloride in known manner which will be later discussed in detail. In the third stage of Fig. 2, the developable ground is illustrated after the etching has taken place, the casting sections 4a, corresponding to half-tone and shadows, being exaggeratedly shown as much deeper than the preserved high-light cavity; such difference is also shown in the cast 11a, of the fourth stage, where the half-tone and shadow dots 9, are much higher than the high-light dot 5a. In practice, when the structure of the first stage is etched, the difference in height may not be so pronounced for the resulting surface is printable and also susceptible of improvement by sanding off the surplus of matter in known way.

Another form of the invention is shown in the four stages of Fig. 3. In the first, the general outline in the structure of the element is the same as before, but two substances are utilized in the body. The upper section 6, is made of copper or equivalent, in a thickness substantially corresponding to the depth of the cavities 7a, which

end at the surface of a second thickness of matter 10, adhered to the first thickness and made of nickel or substance equivalently insoluble in ferric chloride or whichever solvent be adopted for the upper thickness 6. In the second stage of Fig. 3, the element appears protected by a negative resist of gelatine 8a, which, for a fine patterned ground, may correspond to a line subject. In the third stage of the same figure the element is illustrated after the etching, the high-light cavity being preserved and the shadow values 4b shown with separating small areas similar to "flash" dots in regular cuts which can be easily eliminated if desired by prolonging the etching. In the fourth stage the cast 11b shows the preserved highlight dot 5b and the shadow values 9a which are now all on the same plane. This final plate has levelled values as the usual half-tone printing plate and the dots are sharp and even surfaced due to the insoluble section 10 which stops the etching in depth. This type of element affords to utilize a variety of forms in the cavities, for as long as the insoluble thickness stops the etching it would be a question of time to develop the high-light values into darker ones. I may produce the stratified material by stamping a copper foil of suitable thickness and then deposit the nickel by the current; but of course any insoluble substance, as a cured phenolic plate, may serve as support. The copper may also be deposited electrolytically. Or the copper may be welded to or deposited on a hard metal and stamped thereon. In fact the pair of substances adopted may be easily joined by a number of methods freely practiced in different arts.

In Fig. 4, another form is illustrated in which the element of the first stage is similar to the one in the preceding figure, and has the soluble section 6, of copper or equivalent, and the unetchable section 10, of nickel or other equivalently insoluble substance. In this element, however, the two thicknesses are not put in contact, but separated by single or plural thicknesses of matter of varied solubility, of which the one illustrated as example in 12 is made of aluminum or equivalent. As the selective protection of the element has been illustrated in Figs. 2 and 3, the second stage of Fig. 4 shows the already etched element. It may be noticed that the cavities 7b of the first stage are not sharp but represent larger dots than high-lights which by the etching of the second stage are widened into stronger values, with the exception of the preserved cavity that would correspond in the original to a high-light section. After the etching shown at the second stage the intermediary thickness 12 forms the bottom of the moulding values 4c, for a non-acidified solution of ferric chloride does not substantially etch aluminum, which may also be protected. In the third stage the element, now without the gelatine resist, has been submitted to a second etching with hydrochloric acid which does not attack the copper thickness 6, but dissolves the aluminum thickness 12 down to the unetchable nickel section 10, the light half-tone protected cavity, as corresponding to a high-light section of the original remaining preserved. By such second etching the casting values of the tones 14 are deepened in the thickness 12. In the fourth stage the half-tone and shadow printing values 15, of the cast 11c, appear raised above the preserved high-light section 5c, which will not be printable. This is the reason why the ground in the element of the first stage of Fig. 4 has

been illustrated as having depressions which do not sharply end, for as long as the high-lights will not etch and will print no dots, the sharpness of these casting values is immaterial. The resulting printing surface 11c, in Fig. 4, corresponds then to a half-tone with pure whites as those utilized in photo-lithography. As to the thickness 12 it may be built as to provide in several strata different degrees of depth and to suit the desired difference of height in the values. In the same Fig. 4, the first and second stage show, as example, other means 13 for controlling the etchable zones which may equivalently consist of surface protection or unetchable matter 15 suitably distributed and purported to delay the etching of given sections in order to attain special results and effects that is not considered necessary to illustrate. In other words, whether bare or protected, the surface of the ground will hold 20 the resist or other control for the selective etching, but it may be advisable in certain cases that the sections at the outer surface of the ground in immediate contact with the controlling element be not directly etchable and should disappear only by undercutting, and this in order to minimize the danger of separation of the resist during the etching. In the example, the minute depressions of pyramidal shape sharply end in dots at the bottom, but on the outer surface are 30 separated by thin walls similar to gravure pockets, and the means 13, 13, may be provided for protecting the outer sections of the walls, or may be suitably distributed in many other forms to control the etching.

35. In Fig. 5 three stages are presented showing a manner of producing a casting mould in other ways different from the ones already described. In the figure the bare element and the final cast are omitted as being identical to the first 40 and fourth stages of Fig. 3. Although other examples could be presented, the way adopted in Fig. 5 corresponds to a half-tone mould produced by hand on the developable moulding element of the invention. In the first stage of this figure the cavities in the copper ground appear protected by three varnishes of which 16 and 17 are soluble in two different solvents, and 18 in water. These varnishes are colored in white, gray and black respectively, so that an artist can 50 paint a subject on the plate. Rather than using a greater number of varnishes and selective solvents, or protections of varied permeability, it is preferable to use the three fundamental values and give selective etching to the half-tones by 55 successive re-etching operations. When the protected plate of the first stage in Fig. 5 is put into the solution of ferric chloride the protection 18 dissolves in the water, and the shadow sections are attacked by the solution as shown in 60 the second stage. After the shadows are suitably etched the plate is withdrawn from the bath and the half-tone protection washed away in its solvent. When etched again the shadow casting values 19 will have their full development as 65 seen in the third stage, while the half-tone cavities 20 will be formed, and the high-light casting values 16 will remain preserved. As the high-light and extreme shadow values, respectively 70 protected and unprotected are now unchangeable, any gradation desired at selective sections of the half-tones can be produced by re-etching the insoluble thickness 10 showing by contrast with the color of the copper the progress of the operation. The resulting cast will print an artistic half-tone image. If desired the same meth-

od can be applied to the element of Fig. 4 to produce an image with pure whites, the second etching of the section 12 in that figure being made after the selective discharge and the desired re-etching of the values have been performed. Such way of performing the selective discharge of matter at different areas of the developable moulding ground is only presented as example of possible variations for the same results may be attained in other manners as formerly stated.

In the example chosen to demonstrate the invention, the selective protection is a photographic gelatine resist shown in the second stage of both Fig. 2 and Fig. 3.

The processing follows in general lines the etching system usually practiced in photogravure. Such technique is so widely known that the discharge of matter from the developable moulding element could be disclosed by referring to the literature on the subject. However, there are certain points in which the general technique may be modified and advantages and simplifications which can be adopted. I use as master record for the reproduction a positive transparency reversed from right to left. To sensitize the regular black tissue on the market I utilize a bath with a bichromate concentration of 3 percent, or the known spirit sensitizer. I usually expose to photoflood lamps and, as there is not any screen to be printed, no precautions about the light source need be taken. Any photographic printing frame is satisfactory. I may use the developable moulding element of Fig. 2, which is a high-light moulding ground of copper. This is freed of grease by the known treatment with potash followed by dilute hydrochloric acid. The element is then well rinsed and left under water for the transferring. Unless for a number of pictures, requiring transferring time, water-spirit may be dispensed with and plain water transferring adopted. The tissue is placed in the water, freed of air-bells and watched until the curling begins to disappear; then it is turned face down and at the moment when it looks flat, it is brought into contact with the copper ground and lightly squeezed on the last, preferably under water. Then the two are taken out, sponged and put to dry. At this point it is interesting to note that no pressure should be exercised to secure the adherence of the resist which at the initial contact is only held by the outer surface of the walls of the cavities then filled with water. This water is not to be disposed of by squeezing or other forms of pressure which might harm the image; on the contrary, it should be left alone, for it is gradually absorbed by the upper layers of gelatine as the drying takes place on the surface, and a sort of vacuum suction develops inside of each cavity which seems to bring the tissue into contact with the inner walls of the depressions. The development is performed as usually and the drying of the resist adjusted to working room conditions. When the outer surface of the ground is protected as in 13, Fig. 4, the etching does not require special precautions for the protection is equivalent to the screen printed on the ordinary resist of photogravure. But when, as in the example now being described, the ground is bare, it must be considered that the walls of the cavities are also etched under some sections of the resist and while the adherence persists it must be carefully handled. Of course, such is not the situation in a surface-protected ground, which would allow to carry the etching in several baths and down to the 35

Bauiné concentration, although, even then, it should be remembered that the high-lights must be absolutely preserved from any etching. When the developable ground shown in Fig. 3 is utilized, the unetchable bottom behind the copper surface shows the image in all detail, and a selective etching may be carried accordingly, for the printing depth is limited and only the values in surface have to be considered, which is one of the greatest advantages of the process.

After the etching is finished the now developed ground is cleaned in potash, and the oxide removed in weak hydrochloric acid. The mould is then ready for use. And this first product of the invention will be suitable for all casting purposes.

The second product of the invention is the cast, which may be formed in any desired way and with any moulding material. In the line of thermoplastics, any number of cuts may be produced of very light weight, suitable for mail service of a chain of syndicated newspapers, for instance. With melted alloys, printing blocks may be produced in a composition machine, by an attachment that I have devised, in the same manner as lines of text are cast. Cuts may be obtained in vulcanized rubber, in cured phenolic resins, as well as in cold moulding of setting materials. The new block will be most suitable for stereotyping, due to the open shape of the dots without the dangers of dampness and heat when drying the mats on the form. It will be in general, an all purpose product in photomechanical reproduction.

Summarizing: the means, ways and products of the invention, as disclosed in the example, will permit to indirectly produce a half-tone printing block of the best quality, not only without utilizing a process-record, but even without the optical transformation of the values.

The invention also permits to produce a half-tone of the lithographic type in which the whites are pure, as shown in Fig. 4, by an additional etching performed in known manner. In this case only half-tones and shadows are printable.

It further allows to produce a cut in which only highlights and shadows are printable by utilizing a resist of a line subject as shown in 8a, Fig. 3. It may also furnish a block in which only the shadows are printable, if the resist of the second stage in Fig. 3, is used as protection for the element of Fig. 4, to obtain pure whites. This last result, for a fine patterned ground, will be equivalent to a line cut.

A typical feature of the new cast products is that they are homogeneous, and that the projections representing the values show the appearance of geometrically similar figures with truncated tops of different areas and clean edges which are developed in the moulding ground when the etching of the cavities is stopped by the unetchable bottom. This permits to identify a plate produced by the process because when projections are ground down to truncated structures, as in some processes of the prior art, it is necessary to fill up the back in order to bring them to the same plane, while if the projections are flattened by pressure into an apparently truncated form they would show a somewhat nail-headed top and a body distortion which is not found in the article of the invention.

Besides variations in results, by using or combining the described and illustrated means and ways of the invention, these are also susceptible of modifications and substitutions within the scope of the achievement. It may be observed,

for instance, that the difference between the element presented in Fig. 1, and those of the other figures, is not merely the fact that the last are not sensitive to light, but that the etchable or dischargeable zones are insensitive, for the resist transferred and developed on the insensitive ground would be equivalent to a sensitive coating that could be extended on it and suitably processed for the same purpose, and yet the discharge of matter would not be made from the sensitive but from the non-sensitive part of the element. It may also be noticed that the simultaneous production of relief casting values and photoengraving printing values by the etching step in a suitable structure is independent of the means to selectively obtain it, as long as even light values thrown on a ground covered with an etching solution may render this active or inactive and determine a selective effect. It may equally be realized that the etching of metals described in the example is one of the many forms of discharging matter from a ground, which may be built from other suitable substances susceptible of being simply dissolved, or that the metals instead of attacked by an etching solution may also be discharged by the electric current in known manner. It may be considered besides that a stratified and selectively etchable ground may be combined both in a sensitive or insensitive element to produce raised values, all within the same fundamental idea. And it finally must be borne in mind that requirements in a given case are relative within operativeness, for while the depressions should decrease in cross-sectional area for a ground of a single substance, they need only to end sharply if a second substance at their bottom, stops the discharge in depth; and that in the example of Fig. 4, for instance, where the high-lights are not printable they need not end sharply at all.

After having described to the best of my knowledge the present invention, I wish to be understood that the present disclosure is for the purpose of illustration only and that the invention includes any variations and equivalents in means, ways and products within the scope of the following claims.

In my achievement, including the example to demonstrate the invention, I believe to be new and useful, and as such, I claim:

1. In a developable moulding element for a printing surface, a ground including a first thickness of matter impermeable to and gradually soluble in a solvent, having on the upper side depressions or recesses sharply ending at the lower side, such depressions or recesses showing the reversed shape of a printable pattern corresponding to a high-light tint; and a second thickness of different matter unetchable in and impermeable to said solvent adhered to the lower side of the first thickness.

2. In a developable moulding element for a printing surface, two thicknesses of two different materials adhered to each other, the upper thickness corresponding to the casting side of the element showing a plurality of small cavities decreasing in cross-sectional area from its surface and sharply ending substantially at the contacting area with the lower thickness, such cavities forming a pattern having the reversed shape of a highlight printable surface, said materials differently reacting to a solvent in which the one of the upper thickness is gradually soluble, and that of the lower thickness substantially insoluble.

3. In a developable moulding element for a printing surface, three thicknesses of three different materials attached in superposition, the material in the upper thickness corresponding to the casting side of the mould having a plurality of depressions or recesses of the same depth substantially ending at the contacting area of the first and second thicknesses, the respective materials in each of these two thicknesses each soluble in a solvent in which the other material and that of the third thickness are substantially insoluble.

4. In an element developable into a mould for a printing surface a soluble ground carried by an insoluble support, said ground formed by several strata of different materials arranged in succession, each material soluble in a solvent in which the other ones are insoluble, the outer stratum showing through its thickness a plurality of depressions corresponding to the reversed shape of a printing pattern for a tint.

5. In an element developable into a mould for a printing surface, a thickness of etchable matter having a number of small cavities showing the reversed shape of a typographically printable pattern corresponding to a light tint, and means to modify the extent of the etching at selected sections of said thickness of matter, said means equally affecting every one of the cavities.

6. In an element developable into a mould for a printing surface, soluble matter forming a thickness having a plurality of minute depressions or recesses showing the reversed shape of a typographically printable pattern for a light tint, and insoluble second matter selectively distributed to modify the area of the soluble zones in the first matter, said second matter equally affecting each one of the depressions.

7. In a developable moulding element for a printing surface, a thickness of soluble matter having a plurality of small depressions or recesses showing the reversed shape of a high-light printable pattern, and means to protect the soluble thickness of matter at the outer surfaces in the spaces between the different cavities.

8. In a combined foundation developable by etching into a moulding element for a printing surface reproducing a subject, a thickness of copper having on one side a plurality of small cavities sharply ending at the other side; a second and continuous thickness of matter insoluble in ferric chloride adhered to the copper substantially at the ending plane of the depressions; and a third thickness of removable matter upon the thickness of copper, having areas of varied permeability in correspondence with the values of the subject.

9. In a foundation developable by etching into a moulding element for a printing surface reproducing a subject, in combination, an etchable ground having the reversed shape of a high-light printable pattern; means to modify the extent of the etching at selected sections of said ground; and means to proportionate the time of the etching to the values of the subject at different areas of the ground.

10. A method of indirect photomechanical reproduction which comprises producing an etchable moulding ground characterized by having on the casting side a number of small depressions or recesses showing the reversed shape of a high-light printable pattern; producing in known manner, transferring, developing and drying on said ground a negative carbon-tissue image of the original to be reproduced; etching the ground and cleaning and drying the resulting mould;

taking a cast therefrom; and inking and printing it.

11. A method for the indirect production of a printing surface which comprises making a moulding ground by welding two thicknesses of matter of which one is etchable and the other unetchable in a solvent, the etchable thickness corresponding to the casting side of the ground and characterized by having a number of minute cavities sharply ending at the contacting plane of the two thicknesses and showing the reversed shape of a high-light printable pattern; then selectively etching said ground at different areas for different lengths of time; and finally taking a cast from the resulting mould.

12. A method for the indirect production of a printing surface with pure whites which comprises making a moulding ground by joining three thicknesses of different substances, two of which being soluble in different solvents and the third insoluble, the outer soluble substance corresponding to the casting side of the ground and characterized by having a plurality of small depressions or recesses ending at the contacting plane with the second soluble substance; selectively etching said ground in different areas for different lengths of time with one of the solvents; re-etching the ground with the second solvent; and taking a cast from the resulting mould.

13. In the indirect reproduction of a printing surface the step of developing high-light casting values into half-tone and shadow casting values which comprises producing the high-light casting values in a ground, these values consisting in minute depressions or recesses decreasing in cross-sectional area and sharply ending at the same plane; and then enlarging the cavities by discharging matter from the ground at different areas in different proportions.

14. In the indirect reproduction of a printing surface, the step of developing high-light casting values into half-tone and shadow casting values which comprises producing the high-light casting values in a soluble ground, these values consisting in sharply ending cavities having their bottoms substantially at the same plane; providing in said ground means to stop the solubility of the ground substantially at the ending plane of the cavities; and then enlarging the cavities by dissolving the ground in different proportions in different areas.

15. In photomechanical reproduction, the step of transforming photographic values in depth into casting values for photomechanical values in surface, which consists in first producing a ground having depressions or recesses decreasing in cross-sectional area and sharply ending at the same plane; providing in said ground means to protect the areas under the bottom plane of the recesses; and then discharging matter from within said cavities at different areas of the ground proportionally to the photographic values.

16. In a mould for a printing surface, a thickness of matter having a plurality of cavities decreasing in cross-sectional area, a number of said cavities showing at their bottoms minute graphic sections corresponding to high-light values; and another number of cavities showing larger bottom values; the outline of these second cavities substantially corresponding to truncated forms of figures geometrically similar to the shape of the first cavities.

17. In a mould for a printing surface, two thicknesses of material adhered to each other,

the upper thickness corresponding to the casting side of the mould showing a plurality of depressions or recesses decreasing in cross-sectional area and substantially ending at the plane of adherence of the two thicknesses, some of these depressions having a sharp bottom and some other ending in larger areas, the shape of these second depressions substantially corresponding to truncated forms of figures geometrically similar to the shape of the sharply ending recesses, said upper thickness supported by the lower thickness which furnishes the bottom for the truncated depressions.

18. In a mould for a printing surface, three thicknesses of matter in superposition and adhered to one another, the upper first thickness showing a plurality of minute depressions or recesses of which some are larger than the others, the smallest ones ending at the plane of contact of the first and second thickness, and the larger ones at the contacting plane of the second and third thickness, said second thickness representing the difference of depth of the two kinds of depressions and correspondingly the difference in height of printing values in a cast taken therefrom, that difference being such that relief values corresponding in the cast to the smallest depressions will be typographically unprintable and the high-lights will be pure.

19. In a photomechanical printing element, a body of solid and continuous material of even thickness showing at the printing side a plurality of small projections of different sizes decreasing in cross-sectional area, the smallest of said projections ending in sharp vertices corresponding to high-light values, and the larger ones proportionally higher and ending in tops of greater printing areas, the outline of the larger projections substantially being a truncated form of a figure geometrically similar to the shape of the smallest ones, a characteristic of said projections being the clean intersection of the sides and tops of the figures.

20. In a printing surface, a body of solid and continuous material having on the printing side a plurality of minute projections of different sizes, decreasing in cross-sectional area and all ending substantially at the same plane, some of these projections showing sharp vertices and the others larger tops, the outline of the last corresponding to a form of a figure geometrically similar to the shape of the sharp projections.

21. In a printing surface, a body of solid and continuous material showing a number of minute projections representing whites and black values, and correspondingly having printing tops of different sizes, the smallest ones representing the whites ending at a lower plane than the ones representing the black values, the difference in height being such that the smallest projections will not print typographically and the whites will be pure.

22. In a printing surface, a body of solid and continuous material of even thickness having a number of small projections with printing areas corresponding to high-light and tone values, these projections decreasing in cross-sectional area, having different sizes with correspondingly varied top areas, and, up to a plane passing by the vertices of the sharpest ones, showing all the complete or truncated outline of geometrically similar figures.
